UNITED STATES PATENT OFFICE

162,176

EXHAUST PIPE EXTENSION

Leonard Kaplan, Chicago, Ill.

Application July 5, 1950, Serial No. 10,958

Term of patent 14 years

(Cl. D14—6)

To all whom it may concern:

Be it known that I, Leonard Kaplan, a citizen of the United States, residing at Chicago, State of Illinois, have invented a new, original, and ornamental Design for an Exhaust Pipe Extension, of which the following is a specification, reference being had to the accompanying drawing, forming a part hereof.

Fig. 1 is a top plan view of an exhaust pipe extension showing my invention,

Fig. 2 is a rear elevational view thereof, and
Fig. 3 is a bottom perspective view thereof.

I claim:

The ornamental design for an exhaust pipe extension as shown.

LEONARD KAPLAN.
